FRANK B. JONES, OF ALTOONA, PENNSYLVANIA.

STEAM-TRAP.

1,340,958.

Specification of Letters Patent.

Patented May 25, 1920.

Application filed September 22, 1919. Serial No. 325,440.

To all whom it may concern:

Be it known that I, FRANK B. JONES, a citizen of the United States, and a resident of Altoona, in the county of Blair and State 5 of Pennsylvania, have invented certain new and useful Improvements in Steam-Traps, of which the following is a specification.

The invention relates to improvements in steam traps intended, more especially, for 10 the radiators of car heating systems, and it consists in the novel features, structure and combinations of parts hereinafter described, and particularly pointed out in the claims.

The object of my invention is to produce 15 a steam trap of high efficiency and of simple and durable construction.

In practice, the steam trap of my invention is applied to the lower pipe of a radiator and its purpose is to permit water of 20 condensation and the like to drain from the radiator, as occasion may require, and to automatically close the outlet from the radiator when the latter, due to the steam entering the radiator, has attained a sufficient 25 degree of heat. The steam trap of my invention embraces a valve and a thermostatic element which, when in a state of contraction, will permit said valve to open and the water to drain from the radiator and which 30 when a sufficient degree of heat has been attained will by its expansion close said valve and maintain the same in closed position until another situation arises in which it may be desirable to drain the radiator.

The invention will be fully understood 35 from the detailed description hereinafter presented, reference being had to the accompanying drawings, in which:

Figure 1 is a vertical longitudinal section 40 through a steam trap constructed in accordance with and embodying the invention;

Fig. 2 is an end view of the same taken from the left hand end of Fig. 1;

Fig. 3 is a sectional view, partly broken 45 away, of the thermally expansive element constituting a portion of the trap, and

Fig. 4 is a detail view showing a portion 50 of a radiator and steam pipe lines, with the steam trap of my invention illustrated in position in connection with the radiator, a portion of the car flooring being indicated in section.

In the drawings, 10 designates the body or main casing of the trap, which casing has 55 an internally threaded branch 11 and is internally threaded at its outer end, as at 12,

and externally and internally threaded at its inner end, as at 13, 14, respectively. The body of the casing 10 is of general cylindrical outline and in the lower portion of its 60 interior has a downwardly converging floor surface 15 which extends partly over and leads into the branch 11, to which is connected a drain pipe 16, which normally will be an inch pipe and about seven inches long 65 and receive at its lower end a reducer or coupling 17 located at the upper end of a main drain pipe 18 which preferably will be a two inch pipe and ordinarily about twelve inches long, although I do not limit 70 my invention to the proportions of the pipes 16, 18, since said proportions may vary to suit such conditions as may be met in practice.

The internally threaded inner end of the 75 body casing 10 has screwed into it a plug 19 which contains an interior chamber 20 and a polygonal outer head 21 adapted to receive a wrench. The plug 19 when screwed into the inner end of the casing 10, 80 may be keyed or locked therein by means of a plate 22 and screw 23, said plate having a lower edge to engage the head 21 of the plug and an upper end adapted to a recess or groove 24 formed in the end of the 85 casing 10, as will be readily understood by reference to Figs. 1 and 2. It is desirable that the plug 19 be secured in fixed position, and the means I have referred to permit the accomplishment of this result. The head 21 90 is less in diameter than the main body of the plug 19, and hence may enter the lower pipe 25 or its coupling 26 of the radiator. The plug 19 is formed with a through passage 27 leading into the interior of the cas- 95 ing 10, and at its inner end said plug has pivotally secured to its upper portion a valve 28 adapted to swing on the arc of a circle and carrying a packing 29 to engage a valve seat 30 formed about the inner end of the passage 27, said packing being preferably secured to the lower portion of the swinging valve 28 by means of a screw 31. Normally the valve 28 will hang downwardly 100 with its packing 29 against the valve-seat 30, but in the present instance I make use of a spring 32 whose tendency is to move the valve 28 and its packing 29 inwardly from the valve seat 30. The spring 32 is contained within the chamber 20 of the plug 105 33 and is mounted upon a threaded rod 33 screwed into the head 21 and engages the

inner face of the valve 28. The spring 32 acts to move the valve 28 and its packing 29 in a direction from the seat 30, but in this regard the spring 32 is controlled by 5 the thermostatic element 34 having at its inner end an internally threaded head 35 which is in predetermined relation to the outer face of the valve 28.

The head 35 is in the form of an internally threaded sleeve and is screwed upon and pinned to a threaded stud 36 carried by the head 37 which is rigidly secured to the inner end of the thermostat 34. The thermostat 34 extends longitudinally of the 15 casing 10 and has secured to its outer end a head 38 formed with an internally threaded socket 39 within which is screwed and pinned the reduced threaded end 40 of a main spindle 41 whose outer end is furnished 20 with a suitable handle 42.

Within the outer end of the casing 10 is screwed a bonnet 43 which is formed at its outer end with an annular flange 44 and a reduced externally threaded gland member 25 45 upon which is screwed a cap-nut 46 which constitutes the other gland member and confines the packing between itself and the member 45 and around the spindle 41 as shown in Fig. 1.

30 The spindle 41 has two spiral threads numbered 47, 48, respectively, and the interior of the neck of the bonnet 43 is threaded to engage the aforesaid thread 47, which will usually be a substantially square thread 35 with about seven turns or convolutions to an inch. Upon the threaded portion 48 of the spindle 41 is screwed a cap frame 49 whose inner edge 50 engages the annular flange 44 on the bonnet 43. Upon the 40 spindle 41 and engaging the outer end of the frame 49 I provide a jam-nut 50 for locking the spindle 41 in fixed position.

In assembling the parts of my steam trap I necessarily secure the thermostat 34 in 45 predetermined relation to the valve 28, so that said valve may open when water and air are to escape from the radiator through the passage 27 and be closed when steam enters the casing 10 by the expansion of 50 the thermostat 34. In adjusting the relation of the thermostat 34 with the valve 28 I make use of the thread 47 on the spindle 41 and thereafter I lock the thermostat in its fixed position by means of the frame 49, 55 jam nut 50 and screw thread 48.

The several parts of the steam trap are durably constructed and easily assembled, and in addition the trap is efficient in operation. The thermostat 34 is of the diaphragm 60 type and capable of ready contraction and expansion. The internally threaded head 35 may be replaced, when worn, by a new corresponding head at very small expense, and when necessary the plug 19 may be 65 readily withdrawn from the casing 10,

should any occasion arise necessitating an examination or repair of the valve 28. The flooring 15 in the casing 10 serves to direct the water of condensation into the drain pipe 16, and said flooring extends over the 70 edges of the upper end of the drain pipe so as to direct the water directly into said pipe on a line inwardly from the joint between the pipe 16 and branch 11.

What I claim as my invention and desire 75 to secure by Letters-Patent, is:

1. A steam trap comprising a main casing to be connected with a radiator and a drain pipe, a plug screwed into the inner end of said casing and having a through passage at 80 its lower side and a valve hinged at its upper end and carrying packing adapted to close said passage, and a thermostat within said casing adapted when in its expanded state to maintain said valve closed. 85

2. A steam trap comprising a main casing to be connected with a radiator and a drain pipe, a plug fastened within the inner end of said casing and having an exposed polygonal head, a through passage at its lower 90 side and a valve hinged to the inner end of said plug and adapted to close said passage, and a thermostat within said casing adapted, when in its expanded state, to maintain 95 said valve closed.

3. A steam trap comprising a main casing to be connected with a radiator and a drain pipe, a plug screwed into the inner end of said casing and having a through passage at its lower side and a valve hinged at its 100 upper end and adapted to close said passage, means for locking said plug when in position against rotary movement, and a thermostat within said casing adapted, when in its expanded state, to maintain 105 said valve closed. 95

4. A steam trap comprising a main casing to be connected with a radiator and a drain pipe, a plug fastened within the inner end of said casing and having a through passage 110 at its lower side, an interior chamber and a valve hinged at its upper end and adapted to close said passage, a spring within said chamber normally acting to open said valve, and a thermostat within said casing adapted, 115 when in its expanded state, to maintain said valve closed.

5. A steam trap comprising a main casing to be connected with a radiator and a drain pipe and having an inlet passage at its inner end, a valve within said casing for controlling the passage thereinto from the radiator, a thermostat of the diaphragm type within said casing having at its inner end a threaded stem and an internally threaded head thereon adapted on the expansion of the thermostat to close said valve, means for adjusting said thermostat with relation to the valve, and means for locking the thermostat in its adjusted position. 120 125 130 135

6. A steam trap comprising a main casing to be connected with a radiator and a drain pipe and having an inlet at its inner end and an internally threaded bonnet at its outer end, a valve within said casing for controlling the passage thereinto from the radiator, a thermostat of the diaphragm type in said casing having at its inner end a head adapted on the expansion of the thermostat to close said valve, a spindle connected with the outer end of said thermostat and threaded to engage the thread in said bonnet and also being threaded at its outer end, and threaded means on the outer 15 threaded end of said spindle for locking said spindle against rotation after the thermostat has been adjusted with relation to said valve.

7. A steam trap comprising a main casing to be connected with a radiator and a drain pipe and having an inlet at its inner end and an internally threaded bonnet at its outer end, a valve within said casing for controlling the passage thereinto from the radiator, a thermostat of the diaphragm type in said casing having at its inner end a head adapted on the expansion of the thermostat to close said valve, a spindle connected with the outer end of said thermostat and threaded to engage the thread in said bonnet and also being threaded at its outer end, and threaded means on the outer threaded end

of said spindle for locking said spindle against rotation after the thermostat has been adjusted with relation to said valve, 35 said bonnet having at its outer end an annular flange, and said means on the outer end of said spindle for locking the same comprising a frame threaded to engage the thread on said spindle and at its inner edge 40 being adapted to seat against said flange and a jam nut on said spindle at the outer end of said frame.

8. A steam trap comprising a main casing to be connected with a radiator and a drain pipe and having at its inner end an inlet 45 and a valve therefor, a thermostat in said casing adapted on the expansion of the thermostat to close said valve, and means for adjusting the relation of the thermostat and valve, said casing having an integral branch for connection with the drain pipe and a downwardly converging inner flooring extending inwardly over the bore of said branch and adapted to drain the water directly into said pipe inwardly beyond the joint between the pipe and the branch. 55

Signed at Altoona, in the county of Blair and State of Pennsylvania, this 19 day of Sept., A. D. 1919.
